UNITED STATES PATENT OFFICE.

LEWIS F. GRISWOLD, OF MERIDEN, CONNECTICUT, ASSIGNOR TO THE CHARLES PARKER COMPANY, OF SAME PLACE.

DESIGN FOR A WEIGHT FOR EXTENSION-LAMPS.

SPECIFICATION forming part of Design No. 13,968, dated June 5, 1883.

Application filed April 23, 1883. Term of patent 14 years.

To all whom it may concern:

Be it known that I, LEWIS F. GRISWOLD, a citizen of the United States, residing at Meriden, in the county of New Haven and State of Connecticut, have invented and produced a certain new and original Design for Weights for Extension-Lamps; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 represents a vertical central section through a lamp-weight of my newly-designed form and construction, and Fig. 2 represents a plan view of the same.

The leading feature of said design consists in a circular cavity extending down from the top of the weight and a shell or wall exterior to said cavity.

In the accompanying drawings, A designates the weight, which is of annular form, having its inner side vertical and its outside sloping from top to bottom. To increase the beauty of this exterior face, it is broken below the middle of the weight by a circular groove, c, which is angular in cross-section. A broader groove, c', which is curvilinear in cross-section, fills the space from the lower edge of groove c to the bottom of the weight. These grooves c c' do not, however, materially affect the general tapering contour of the outer face of the weight.

B designates a deep annular cavity, extending down from the top of the weight, toward

the bottom thereof, and of such width as to leave a thin exterior shell, C, which constitutes a wall between said cavity and the outside of the weight, and a thicker wall, D, between said cavity and the circular opening E, through the interior of the weight. The sides of cavity B are gently inclined, so that the weight, as shown in Fig. 2, has a pleasing and ornamental appearance, presenting, as seen from above, two concentric walls, with flat tops of different width, sides that slope together, an intervening annular cavity, and a central circular opening.

I claim—

1. The design for a weight for extension-lamps herein shown and described, consisting of the annular wall D and shell C, connected at the bottom, and the annular groove or cavity B between them.

2. The design for a weight for extension-lamps herein shown and described, the same consisting of the outer face of the weight inclining or tapering inward from the top to the bottom, and having groove c, which is angular in cross-section, and groove c', which is curvilinear in cross-section, and the inner wall, D, and the outer shell, C, having their proximate faces inclined downward toward each other and separated by an annular groove or cavity, B.

In testimony whereof I affix my signature in presence of two witnesses.

LEWIS F. GRISWOLD.

Witnesses:

DEXTER W. PARKER,
RALPH A. PALMER.
